UNITED STATES PATENT OFFICE.

WARREN NOBLE, OF DETROIT, MICHIGAN.

OIL-DISTRIBUTING DEVICE.

Application filed June 27, 1927. Serial No. 201,851.

This invention relates to engines or mechanisms employing oil for lubricating or other purposes wherein it is desirable that provision be made for cleaning of the oil, for the 5 circulating of the oil after cleaning to certain parts of the mechanism as required, and also for the raising of the cleaned oil to elevated parts of the mechanism.

In its more particular application the invention has for its object to provide in an engine means for centrifugally cleaning oil utilized in connection with the engine mechanism, and means effecting the circulation of the cleaned oil to required parts of the 15 engine mechanism and thereafter back to the centrifuge; the said invention still further contemplating the utilizing of the flywheel of the centrifuge in such a system.

Still further the invention has for its object to combine an oil-cleaning centrifuge with a centrifugal pump arranged to discharge clean oil from the centrifuge to required parts of the engine mechanism; and has as a further object the provision of means whereby 25 the rotor of the centrifuge operates to effect the return of oil from a well or sump to the interior of the centrifuge.

The invention further aims to provide a centrifuge with an annular wall determining 30 the maximum depth of oil in the centrifuge and a centrifugal pump forming part of the rotor of the centrifuge receiving the overflow of the centrifuge and discharging it by a suitable conduit whereby it is led in any required 35 direction.

A further object of the invention is to provide in an engine having elevated mechanism to which clean oil is to be supplied, an oil circulating system having interposed therein an 40 oil-cleaning centrifuge and a centrifugal pump operating with the centrifuge to receive the overflow therefrom and direct it to the elevated mechanism.

An important object of the said invention 45 is to provide for the centrifugal skimming of clean oil from a centrifuge by means of a centrifugal pump forming part of the said centrifuge structure and rotating therewith.

Still further objects or advantages subsidiary or incidental to the aforesaid objects, or resulting from the construction or operation of the invention as it may be carried into effect, will become apparent as the said invention is hereinafter further disclosed.

In carrying the said invention into effect, I may provide, in an engine, a flywheel ar-

ranged in a chamber, the lower part of which forms an oil sump, the said chamber having an elevated well opening from a point substantially above the sump and adapted to receive oil raised by the rotation of the flywheel from the said sump, the said flywheel having an inwardly projecting wall forming an annular chamber in the flywheel adapted to receive oil, whereby the said flywheel may clean oil received in the said chamber by centrifugally separating foreign matter therefrom, and a passage extending from the said elevated well to the interior of the flywheel for the purpose of conveying oil to the said annular separating chamber thereof. The flywheel thus operates as a centrifuge the overflow of which passes over the inner edge of the said annular wall and a further annular wall is provided in spaced relation to the first mentioned wall and flanged within the inner edge thereof whereby the said overflow is received between the two walls and centrifugally discharged into a volute channel within the flywheel casing, from which channel it is in turn discharged to elevated or other parts of the engine mechanism. A return pipe directs the oil back to the sump after it has performed its functions.

All of which is more particularly described and ascertained hereinafter, by way of example, having reference to the accompanying drawings, wherein:

Figure 1 is a fragmentary section of the flywheel casing of an engine embodying the 90 said invention, the section being taken on the line 1^x . . . 1^x of Figure 2;

Figure 2 is a transverse section of the same taken on the line 2^x . . . 2^x of Figure 1, the elevated mechanism of the engine being indicated schematically; and

Figure 3 is a detail sectional view taken on the line 3^x . . . 3^x of Figure 2, the representation of the oil being omitted in this view.

Similar characters of reference indicate 100 similar parts in the several figures of the drawings.

1 indicates a crankcase of an engine provided with a flywheel chamber 2 housing a flywheel 3 which is mounted on the end of the 105 crankshaft 4, the lower part of the said chamber forming an oil well or sump 5 into which the rim of the flywheel extends.

The flywheel is adapted to operate as a centrifuge by the provision of an annular ring 110 or wall 6 extending inwardly of the rim of the flywheel and forming an annular oil-sep-

arating chamber 7 within the rim of the flywheel whereby dirt or heavy foreign matter in oil within the said chamber will be centrifugally separated from the said oil when 5 the flywheel rotates, as will be readily understood, and thrown against the rim of the flywheel.

Oil to be cleaned is received in the sump 5, and, opening from the sidewall of the 10 chamber 2 at a point above the lower part of the annular ring 6 of the centrifuge, there is a well 8 from which a discharge pipe 9 extends in a downwardly inclined direction to the interior of the flywheel centrifuge, so that 15 oil entering the well 8 passes through the said pipe line by gravity into the annular chamber 7 of the said centrifuge, the oil being elevated from the sump into the well 8 by the impelling action of the rim of the flywheel. 20 To facilitate the lifting of the oil by the flywheel into the well 8 in the required manner the chamber 2 may be formed to provide a substantially volute passage 10 extending from the sump to the receiving opening of 25 the said well 8. The arrangement described affords a simple method of transferring oil from the sump to the interior of the flywheel centrifuge, the operation being continuous as long as the flywheel is rotating and there is 30 oil in the sump to be cleaned.

As the annular chamber 7 of the flywheel centrifuge becomes filled with oil, overflow takes place over the inner edge of the wall 6, this overflow oil being clean, and provision 35 is made for receiving this clean overflow oil and pumping it to required mechanisms or locations, the means employed being in the form of a centrifugal pump which operates as a unit with the flywheel centrifuge.

40 This pump is formed by providing a further wall or ring 11 spaced from the wall 6 by spacers 12 and provided with an inner flange 13 extending into the centrifuge through the opening of the said ring 6 but 45 spaced from the inner edge of the said ring, so that the ring 11 and its flange form an annular passage about the inner edge and the outer face of the said ring 6 and co-act with the said ring 6 in forming a centrifugal pump 50 which receives the overflow from the annular chamber 7 of the centrifuge and discharges it into a volute chamber 14 formed in a circum-scribing ring or member 15 situated in the flywheel chamber 2.

55 The end of the said volute chamber 14 opens into a discharge pipe or passage 16 which extends to overhead mechanism, schematically represented at 17, from which the oil is returned to the sump 5 through the re- 60 turn pipe 18.

It is preferred that the pipe 9 discharge into the back of the centrifuge as shown on the drawings so that the oil will follow the path indicated by the arrows in the lower 65 part of Figure 1, whereby the incoming oil

will not contaminate the overflowing clean oil.

Thus, without complication, clean oil from the flywheel centrifuge is centrifugally pumped to any part of the engine mechanism and elevated, if required, to any desired extent within lifting power of the centrifugal pump, and, as the oil after performing its duties is returned to the sump and then elevated by the flywheel into the well 8 from which it descends through the pipe 9 to the centrifuge for recleaning, the cycle will be continuous with an adequate supply of oil as long as the flywheel is operated, and a steady flow of cleaned oil to the mechanism of the engine during its operation is ensured.

70 The centrifugal pump admits of the very simplest form of construction as will be obvious and calls for no independent mechanism for its operation, it being unitary with the flywheel. Further, the said pump forms a very positive means of skimming the cleaned oil from the centrifuge as clean oil rises in the chamber 7 beyond the inner edge 80 of the ring 6.

85 This invention may be developed within the scope of the following claims without departing from the essential features of the said invention, and it is desired that the specification and drawings be read as being merely 90 illustrative and not in a limiting sense, except as necessitated by the prior art.

95 What I claim is:—

1. In combination with a centrifuge, a centrifugal pump including a fluid impelling rotor, said rotor being fixed to and rotatable with said centrifuge and fluid directing means leading to said rotor and located remotely from the inner periphery of said centrifuge.
2. In combination with a centrifuge having an annular wall extending inwardly of the periphery thereof determining the maximum depth of fluid in said centrifuge, a centrifugal pump including fluid impelling rotor carried by said centrifuge and receiving overflow over the inner edge of said wall.
3. In combination with a centrifuge having an annular wall extending inwardly of the periphery thereof determining the maximum depth of fluid in said centrifuge, a further annular wall spaced from and rotatable with said first mentioned wall, means guiding overflow over the inner edge of said first mentioned wall to the space between said walls whereby overflow fluid is discharged centrifugally through the said space between said walls, and a pump casing receiving the discharged overflow.
4. In combination with a centrifuge having an annular wall extending inwardly of the periphery thereof determining the maximum depth of fluid in said centrifuge, a centrifugal pump including a fluid impelling rotor carried by said centrifuge to receive overflow over the inner edge of said wall, and an an-

nular flange on said rotor extending through the opening of said wall to guide overflow from said centrifuge to said rotor.

5. The combination according to claim 3, wherein the said means is in the form of a flange extending from said second mentioned annular wall within and in spaced relation to the inner edge of said first mentioned wall.

6. In combination with an engine flywheel, an annular wall extending inwardly of the periphery thereof whereby an annular centrifuge chamber is provided in said flywheel, a centrifugal pump including a fluid impelling rotor rotatable with said flywheel and receiving and discharging overflow from said centrifuge chamber, and oil supply means opening into said centrifugal chamber.

7. In combination with an engine flywheel, an annular wall extending inwardly of the periphery thereof whereby an annular centrifuge chamber is provided in said flywheel, a centrifugal pump including a fluid impelling rotor rotatable with said flywheel and receiving and discharging overflow from said centrifuge chamber, and oil supply means opening into the back of said centrifuge chamber remote from said rotor.

8. In combination with an engine flywheel, an annular wall extending inwardly of the periphery thereof whereby an annular centrifuge chamber is provided in said flywheel, a further wall spaced from said first mentioned wall and rotatable with said flywheel, means guiding overflow from said centrifuge chamber over the inner edge of the said first mentioned wall to the space between said walls whereby overflow fluid is discharged centrifugally through the said space, and a pump casing receiving the discharged overflow.

9. In an engine, in combination, a flywheel having an annular wall extending inwardly of the periphery thereof whereby an annular centrifuge chamber is provided in said flywheel, an oil sump through which the rim of said flywheel passes, an elevated well receiving oil raised from said sump by the rotation of said flywheel, a conduit directing oil from said well to the annular chamber of said flywheel, and means directing overflow oil from said annular chamber to parts of said engine intended to receive said oil.

10. In an engine, in combination, a flywheel having an annular wall extending inwardly of the periphery thereof whereby an annular centrifuge chamber is provided in said flywheel, an oil sump through which the rim of said flywheel passes, an elevated well receiving oil raised from said sump by the rotation of said flywheel, means directing oil gravitally from said well to the annular chamber of said flywheel, and means directing overflow oil from said annular chamber to parts of said engine intended to receive said oil.

65 11. In an engine, in combination, a fly-

wheel having an annular wall extending inwardly of the periphery thereof whereby an annular centrifuge chamber is provided in said flywheel, an oil sump through which the rim of said flywheel passes, an elevated well receiving oil raised from said sump by the rotation of said flywheel, means directing overflow oil from said annular chamber over the inner edge of said annular wall to parts of said engine intended to receive said oil, and means directing oil from said well to the back of said chamber remote from said wall.

12. In an engine, in combination, an oil cleaning centrifuge comprising a flywheel having an annular wall extending inwardly of the periphery thereof whereby an annular centrifuge chamber is provided in said flywheel, means supplying oil to be cleaned to said chamber, and a centrifugal pump discharging cleaned oil from said chamber, said pump including a fluid impelling rotor carried by and rotatable with said flywheel.

13. In an engine, in combination, an oil cleaning centrifuge comprising a flywheel having an annular wall extending inwardly of the periphery thereof whereby an annular centrifuge chamber is provided in said flywheel, an oil pump through which the rim of the flywheel passes, an elevated well receiving oil raised from said sump by the rotation of said flywheel, means directing oil from said well to the centrifuge chamber of said flywheel and a centrifugal pump discharging cleaned oil from said chamber, said pump including a fluid impelling rotor carried by and rotatable with said flywheel.

14. In an engine, in combination, an oil cleaning centrifuge comprising a flywheel having an annular wall extending inwardly of the periphery thereof whereby an annular centrifuge chamber is provided in said flywheel, an oil sump through which the rim of the flywheel passes, an elevated well receiving oil raised from said sump by the rotation of said flywheel, means gravitally directing oil from said well to the centrifuge chamber of said flywheel, and a centrifugal pump discharging cleaned oil from said chamber, said sump including a fluid impelling rotor carried by and rotatable with said flywheel.

15. In an engine, in combination, an oil cleaning centrifuge comprising a flywheel having an annular wall extending inwardly of the periphery thereof whereby an annular centrifuge chamber is provided in said flywheel, an oil sump through which the rim of the flywheel passes, an elevated well receiving oil raised from said sump by the rotation of said flywheel, means directing oil from said well to the back of the centrifuge chamber remote from said annular wall, and a centrifugal pump discharging cleaned oil from the front of said chamber, said pump including a fluid impelling rotor carried by and rotatable with said flywheel.

16. In an engine, in combination, an oil cleaning centrifuge comprising a flywheel having an annular wall extending inwardly of the periphery thereof whereby an annular centrifuge chamber is provided in said flywheel, an oil sump through which the rim of the flywheel passes, an elevated well receiving oil raised from said sump by the rotation of said flywheel, means directing oil from said well to the centrifuge chamber of said flywheel, a further wall spaced from said first mentioned wall of said flywheel and rotatable therewith, means guiding overflow from said flywheel centrifuge chamber over the inner edge of said first mentioned wall to the space between said walls whereby overflow is discharged centrifugally to said space, and a pump casing receiving and directing the discharged overflow to the parts of said engine intended to receive said oil.

17. In an engine, in combination, an elevated mechanism, an oil cleaning centrifuge comprising a flywheel having an annular wall extending inwardly of the periphery thereof whereby an annular centrifuge chamber is provided in said flywheel, a centrifugal pump elevating cleaned oil from said centrifuge to said elevated mechanism, said pump including a fluid impelling rotor carried by and rotatable with said centrifuge, and means returning oil from said elevated mechanism to the interior of said centrifuge.

18. In an engine, in combination, an elevated mechanism, an oil cleaning centrifuge, a centrifugal pump elevating cleaned oil

from said centrifuge to said elevated mechanism, said pump including a fluid impelling rotor carried by and rotatable with said centrifuge, and means returning oil from said elevated mechanism to said centrifuge.

19. In an engine, in combination, an oil cleaning centrifuge rotating about a horizontal axis, an oil sump through which the periphery of said centrifuge passes, an elevated well receiving oil raised from said sump by the rotation of said flywheel, means directing oil from said well to the interior of said centrifuge, a centrifugal pump elevating cleaned oil from said centrifuge to said elevated mechanism, said pump including a fluid impelling rotor carried by and rotatable with said centrifuge, and means returning oil from said elevated mechanism to said sump.

20. In an engine, in combination, a flywheel housing, an oil cleaning centrifuge comprising a flywheel having an annular wall extending inwardly of the periphery thereof whereby an annular centrifuge chamber is provided in said flywheel, an oil sump in the lower part of said housing through which the rim of said flywheel passes, an elevated well receiving oil raised from said sump by the rotation of said flywheel, said housing having a substantially volute passage formed therein extending from said sump to said elevated well, and means directing oil from said well to the interior of said flywheel centrifuge.

In testimony whereof I affix my signature.

WARREN NOBLE.
